MANIFOLD TRANSFER DEVICE

George U. Lacroix, Holyoke, Mass.

Application June 3, 1935, Serial No. 24,603

4 Claims. (Cl. 282—29)

This invention relates to a manifold transfer device for use in making multiple copies on a typewriter and in general the object of the invention is to simplify the construction and lower the cost of manufacture of such transfer devices.

A further object is to provide an arrangement for facilitating the assembly of the carbon sheets with the copy sheets and thus save the time of the operator in the use of the device. A still further object is to provide means whereby the carbon sheets may be separately and individually replaced when used up, thus contributing further to the economy in the use of the device.

In my previous patent dated June 28, 1932, No. 1,865,115, I have shown and described a manifold transfer device of the general character but of different construction than the one here presented, and the method of use of such a device is fully described therein. In general the function of such a device is to provide means for typing a ribbon copy and one or more carbon copies upon copy sheets which are in the form of continuous superposed strips commonly known as fold packs. The strips have weakened lines of rupture at regularly spaced intervals so that the individual copy sheets may be easily separated from the strips when the typing thereon is completed. Necessary carbon sheets are interleaved with the copy sheets, said carbon sheets however being commensurate in size only with the individual copy sheets and the arrangement thereof in such that after typing each set of copy sheets, the continuous strips may be repositioned with respect to said carbon sheets to bring into registration therewith a new set of copy sheets. In this manner a single set of carbon sheets may be employed for several sets of copy sheets without the necessity of repeating the interleaving operation. A preferred form of my present invention will now be described, having reference to the accompanying drawings, in which,

Fig. 1 is a front plan view of the device assembled with copy sheet strips, a corner of said pack being broken away to disclose the underlying carbon and copy sheets;

Fig. 2 is a longitudinal section of the same along line 2—2 of Fig. 1;

Fig. 3 is a transverse section along line 3—3 of Fig. 1;

Fig. 4 is a view of the extension sheet and carbon sheet in detached relation;

Fig. 5 is a detail view of one rear corner of a carbon sheet and a forward corner of the extension sheet showing the detachable means for interlocking the same;

Fig. 6 is a sectional and schematic view of the typewriter platen and the device in position at the completion of the typing on a set of copy sheets;

Fig. 7 is a similar view to Fig. 6 showing the relative position of said parts when the copy sheets or strips are repositioned with respect to the carbon sheets;

Fig. 8 is a similar view showing the relative position of parts after a completed set of copy sheets has been torn off and in position for typing a new set of copies;

Fig. 9 is a view similar to Fig. 6 in which the extension sheet is placed on top of the copy sheets; and

Fig. 10 is a fragmentary end view to show the guiding and stop devices.

It will be understood that in the drawings, the dimensions, particularly the thickness of the sheets, have been exaggerated for the purpose of 20 clearness in disclosure.

Referring more particularly to the drawings, 1 indicates an extension sheet which may be made of any suitable thin flexible and durable material. For this purpose cloth may be used, 25 treated or otherwise prepared to give it both strength and an attractive appearance. In my preferred form of extension sheet marginal portions 2 and 3 at the sides, and a rear marginal portion 4 are folded upon themselves and stitched 30 to the body of the sheet for reenforcement. The rear marginal portion 4 is preferably stiffened by 35 a suitable insert or stay 4' of stiffening material such as cardboard or celluloid.

At the rear end 4 of said extension sheet near each corner thereof and on the front side, as shown, are secured guiding devices 5 and 6. These are preferably in the form of substantially flat U-shaped pieces of metal which guide the marginal edges of the copy strips 20 and 40 keep said strips in proper association with the extension and carbon sheets. Upon each marginal portion near the rear end of said extension sheet are secured stop devices 7 and 8 as shown. These stop devices are preferably angular pieces 45 of metal each with one arm fastened to the body of the sheet and the other arm extending at right angles thereto. The purpose of these stop devices is to limit the travel of the extension sheet 50 1 around the platen of the typewriter as will be hereafter described.

The carbon sheets which I generalize by the term transfer sheets, are preferably made up as shown in Fig. 4 and comprise an ordinary sheet 55 of carbon paper 9 with a reinforcing thin card-

board strip 10 at the rear edge thereof. The strip 10 is pasted to the rear edge of the carbon sheet and the forward edge of the carbon sheet has a cut away portion 11. The reenforcing strip 10 extends transversely of the carbon sheet, somewhat beyond each marginal edge of the latter as shown, to provide interlocking hook tabs 12 and 13. It will be understood that the width of the carbon sheet is approximately the width of the 10 copy sheets and slightly narrower than the full width of the extension sheet as shown in Fig. 1. The lateral tabs 12 and 13 however are of sufficient length to overlap said marginal portions 2 and 3 of the extension sheet. At each of the forward corners of the extension sheet are provided 15 pockets 14, 15 formed by doubling upon itself marginal portions of said extension sheet which are fastened together by stitches 18 and 19. The pockets thus formed open laterally toward the center of the sheet, for receiving the tabs 12 and 13 of the reenforcing strip 10. The spot stitchings 18 and 19 near the inner edges of said pockets respectively provide means for hooking or otherwise securing by interlocking engagement the 20 hooked tab members 12 and 13 when inserted in said pockets and pulled downwardly thereon as shown in Fig. 5. By this method of detachably securing the carbon sheets to the extension sheet I have added no appreciable thickness thereto and 25 therefore this portion of the extension sheet and its secured carbons may pass easily between the platen 23 and its presser rolls 24 in the operation of the device as hereinafter described.

It will be understood that as many carbon 30 sheets as desired may be employed in association with an extension sheet, the number thereof being varied to suit the particular work in hand since said individual carbon sheets are separately secured to said extension sheet by having the respective tabs 12 and 13 engage in the pockets 14 and 15 as shown. It will also be appreciated that when a carbon sheet has been used up it may be quickly renewed and replaced by another carbon sheet of similar form.

45 It will be noted that in Figs. 1 to 8 inclusive the extension sheet 1 is located on the under side or back of the sheet pack so as to directly engage the platen of the typewriter. In this form the extension sheet may be lengthened if desired so 50 as to be coextensive with the carbon sheets and thus form a reenforcing backing sheet therefor.

Under some circumstances it may be desirable 55 to locate the extension sheet on the top side of the sheet pack as shown in Fig. 9. In this case the extension sheet 1' should be relatively short as shown and not extend over the carbons, since it would then cover the copy sheets when in writing position. Also in this form of arrangement 60 the guide devices 5, 6 should be mounted on the under side (platen side) of the extension sheet, in other words, on the same side as the stop devices 7, 8, which always project from the under side of the extension sheet so as to engage with the platen.

65 The operation and use of my manifold transfer device on a typewriter are as follows. The forward end of a copy sheet strip 20 will be inserted beneath the guiding devices 5, 6 and over the front side of the extension sheet 1, and pulled 70 beyond the forward end of said extension sheet for a distance slightly greater than the length of a single copy sheet, see Fig. 1. Thereupon a carbon sheet 9 is superimposed upon said copy sheet and the tabs 12 and 13 of said carbon sheet are 75 interlocked with the pockets 14, 15 at the forward

corners of the extension sheet. The forward end of the copy sheet is made to register with the forward end of the carbon sheet. In a similar manner successive copy sheets and carbon sheets are superimposed one above the other until the desired number of copy sheets and carbon sheets are assembled, the last copy sheet of course being on top. In this assembly all the front edges of the copy sheets should be in substantial registration with the front edges of the carbon sheets 10 thereby insuring that each underlying copy sheet will be covered by a carbon sheet. The rupture line of the copy strips is indicated at 21 in Fig. 1.

The assembly is then mounted on the typewriter, the forward ends of the superimposed 15 sheets being fed around the platen so as to bring the top copy sheet in position for typing. After the typing has been completed (it being assumed that the typing continued to the bottom of a copy sheet) the parts will be in position as shown in 20 Fig. 6. The operator will then turn the platen by hand to feed the assembled sheets forwardly until the rear ends 21 of the foremost copy sheets and carbon sheets are completely clear of said platen and the parts will then be in the position shown 25 in Fig. 7. The purpose of the stop devices on the extension sheet will now be apparent since at this time the right angle arms will engage the platen and limit any further travel of the extension sheet around the same. It will be understood that the 30 paper table or guide 22 which is at the rear of the platen 23 on the usual typewriter will serve to insure the engagement of said stop devices 9 and 10 against the platen.

In the position of Fig. 7 the rear ends of the 35 carbon sheets are also clear of the platen, the only elements of the assembly now extending around the platen being the extension sheet and the copy strips. The paper release lever of the typewriter (not shown) is then operated to release the grip 40 of the platen presser rolls 24 upon the copy strips which extend around the platen. The forward ends of the copy strips at the portions marked by the cut-outs 11 of the carbons are then grasped by the operator and pulled until the 45 foremost set of copy sheets is completely clear of said carbon sheets which will of course bring a second set of copy sheets in registration with said carbon sheets. The dotted line 21 in Fig. 7 indicates where the finished copy sheets may be 50 torn off. Then the paper release lever of the typewriter is reset and the platen is rotated backwardly to position the assembled carbon sheets and copy strips for typing on a new set of copy sheets. The previously typed copy sheets are then 55 torn off along their weakening lines and the operation may be repeated until the complete fold pack of copy strips is used up. As before stated, individual carbon sheets may be easily and quickly replaced from time to time and thus a 60 assembly of the device is only required for the use of a new fold pack.

While I have described the preferred embodiment in which my invention may be practiced, I appreciate that various changes in the details of 65 construction shown may be readily made and consequently the limitations to what I regard as new in the invention are defined in the following claims.

I claim:

1. A manifold transfer device for use in a typewriter comprising in combination a flexible extension sheet, means for detachably securing one or more carbon sheets, in interleaved relation with copy sheets, to front marginal portions of the 75

extension sheet, said detachable securing means comprising flat strips permanently secured to the rear edge portion of the carbon sheets and provided at each end with flat laterally extending, forwardly and inwardly opening hook-shaped tabs positioned at the rear corners of the carbon sheets, the side marginal portions of the extension sheet being double ply to form flat pockets in which said tabs may be inserted, said plies being secured together at points to form means within the pockets with which the hooks of the tabs may be engaged, the material of the extension sheet and tabs being sufficiently thin so that their combined thickness will pass readily between the platen and pressure applying means of the typewriter.

2. A manifold transfer device for use in a typewriter comprising in combination a flexible extension sheet having means at the rear end thereof to limit its travel around the platen of the typewriter, means for detachably securing one or more carbon sheets, in interleaved relation with copy sheets, to front marginal portions of the extension sheet, said detachable securing means comprising flat strips permanently secured to the rear edge portion of the carbon sheets and provided at each end with flat laterally extending, forwardly and inwardly opening hook-shaped tabs positioned at the rear corners of the carbon sheets, the side marginal portions of the extension sheet being double ply to form flat pockets in which said tabs may be inserted, said plies being secured together at points to form means within the pockets with which the hooks of the tabs may be engaged, the material of the extension sheet and tabs being sufficiently thin so that their combined thickness will pass readily between the platen and pressure applying means of the typewriter.

3. A manifold transfer device for use in a type-

writer comprising in combination a flexible extension sheet having means at the rear end thereof to limit its travel around the platen of the typewriter, means separate from said first named means to guide and support a plurality of superposed copy sheets in alignment on the extension sheet, means for detachably securing one or more carbon sheets, in interleaved relation with copy sheets, to front marginal portions of the extension sheet, said detachable securing means comprising flat strips permanently secured to the rear edge portion of the carbon sheets and provided at each end with flat laterally extending, forwardly and inwardly opening hook-shaped tabs positioned at the rear corners of the carbon sheets, the side marginal portions of the extension sheet being double ply to form flat pockets in which said tabs may be inserted, said plies being secured together at points to form means within the pockets with which the hooks of the tabs may be engaged, the material of the extension sheet and tabs being sufficiently thin so that their combined thickness will pass readily between the platen and pressure applying means of the typewriter.

4. A carbon sheet adapted to be releasably connected to the extension member of a multiple copying device for typewriters, a strip of thin reinforcing material, stiffer than the material of the carbon sheet itself, permanently secured to the rear edge portion of the sheet and provided at each end with flat laterally extending portions in the form of inwardly and forwardly opening hooks forming means for detachably connecting the rear corners of the carbon sheet to the extension member of the copying device said strip being sufficiently thin so that the combined thickness of the carbon sheet and strip will pass readily between the platen and pressure applying means of the typewriter.

GEORGE U. LACROIX. 40
